Des. 221,585
Patented Aug. 24, 1971

221,585

LIGHT FIXTURE

Buell Moore, Houston, Tex., assignor to
Esquire, Inc., New York, N.Y.

Original design application Apr. 10, 1969, Ser. No. 16,662,
now Patent No. 217,637, dated May 19, 1970. Divided
and this application Mar. 3, 1970, Ser. No. 21,725

Term of patent 14 years

Int. Cl. D26—03

U.S. Cl. D48—31

FIG. 1

FIG. 2

FIG. 1 is a perspective view from the bottom and one corner of a light fixture incorporating my design; and
FIG. 2 is a perspective view from the top and opposite corner of such light fixture.

The smooth surfaces on the sides and bottom of said light fixture are windows.

This is a division of design application No. 16,662, filed Apr. 10, 1969, now Design Pat. No. D. 217,637.

I claim:

The ornamental design for a light fixture, substantially as shown and described.
